UNITED STATES PATENT OFFICE.

LE ROY W. TILT, OF BALTIMORE, MARYLAND.

DRAIN GUARD FOR WASHING MACHINES.

Application filed July 7, 1926. Serial No. 120,908.

This invention relates to washing machines of the type having a bottom drain outlet connected to a pump for removing the spent washing fluid from the machine.

More especially the invention relates to a drain guard for washing machines.

In the use of washing machines having a drain for the water which has been used it sometimes happens that an article being washed is drawn into the mouth of the drain and plugs it up. Even where no pump is used for the drainage this is a subject of much annoyance. If a pump is used, as is common in many washing machines this not only is annoying but becomes a source of damage as a small article or a portion of a larger article may be drawn into the works of the pump with resultant destruction of the article and damage and choking of the pump. If the pump is damaged it is, of course, necessary to take it apart and repair or replace the damaged part. If the pump is simply choked but not damaged it still remains necessary to take it apart. All this means loss of time and money.

The principal object of the invention is to provide an improved drain guard for such washing machines which may be readily removed and replaced and which will effectually prevent an article of the wash being drawn into the drain.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a side elevation of a washing machine partly broken away to show the improved drain guard therein.

Figure 2 is an enlarged detail, vertical section through the drain and guard and showing the associated parts.

Figure 3 is a section on the line 3-3 of Figure 2.

In the embodiment of the invention herein disclosed a tub 10 of the ordinary cylindrical shape common in this type of washing machine is shown as provided with a bottom 11. In the bottom adjacent the side wall of the tub is an inverted frusto-conical drain opening 12 from which a pipe 13 ex-

tends to the pump 14. This drain opening is closed during the washing operation by a plug 15 carrying an upwardly extending overflow pipe 16 to which is connected a lift rod 17 terminating near the open top of the tub so that the plug and overflow pipe may be manipulated without making it necessary to dip one's hand in the wash water. These parts are those usually found in such washing machines and, while the clothes are intended to be kept in an inner basket or spinner, yet articles will occasionally get into the space near near the drain and, being hidden by the basket, will be drawn into the drain without being observed.

The guard itself consists of a vertically disposed perforated plate 18 bent to U-shape in plan and having a cover plate 19 fitting the top edge of the plate 18 and provided with an arcuate edge 20 conforming to the curvature of the inner surface of the side of the tub 10. In this top plate is an opening 21 of such size as to slide over the pipe 16 and from this opening extends a slot 22 for the reception of the lift rod 17. Fixed to the bottom of the tub is a leaf spring having a base 23 by which it is secured to said bottom and an upstanding finger 24 engaging the wall 18 to force the end edges of said wall 18 and the arcuate edge 20 of the top firmly into contact with the side wall of the tub 10 whereby the guard is securely held in position to cover and protect the drain opening 12. Nevertheless, the guard may be easily removed by simply lifting it upwardly until it is above the pipe 16 and then moving it inwardly toward the center of the hub to free it from the lift rod.

With the guard in position it is obvious that none of the articles being washed can be drawn into the drain.

There has thus been provided a simple and efficient device of the kind described and for the purpose specified.

Having thus described the invention, what is claimed as new, is:

1. In a washing machine having a tub provided with a side wall and with a drain opening in its bottom adjacent said side wall, a guard of perforated metal covering the drain opening and having one end shaped to conform to said side wall, and spring means carried by the tub and engaging the guard to force it against the side wall thereof.

2. In a washing machine having a tub provided with a side wall and with a drain opening in its bottom adjacent said side wall, a guard of perforated metal covering the drain opening and having one end shaped to conform to said side wall, and a leaf spring having a base portion fixed to the bottom of the tub and an upstanding portion engaging the end of the guard remote from said side wall and forcing the guard thereagainst. 5
3. In a washing machine having a tube provided with a side wall and with a drain opening in its bottom adjacent said side wall, a guard of perforated metal covering the drain opening and having one end shaped to conform to said side wall, and a leaf spring having a base portion fixed to the bottom of the tub and an upstanding portion engaging the end of the guard remote from said side wall and forcing the guard thereagainst. 10
- 15
- shaped to conform to said side wall, and a leaf spring having a base portion fixed to the bottom of the tub and an upstanding portion engaging the end of the guard remote from said side wall and forcing the guard thereagainst, said tub having a plug for said drain opening provided with an upstanding overflow pipe and also having a lift rod carried by the pipe and extending parallel thereto, said guard having an opening for the reception of said pipe and an open ended slot to receive the lift rod. 20 25

In testimony whereof I affix my signature.

LE ROY W. TILT.
